UNITED STATES PATENT OFFICE.

REINHOLD RÜDENBERG, OF CHARLOTTENBURG, NEAR BERLIN, GERMANY, ASSIGNOR
TO SIEMENS SCHUCKERT-WERKE G. M. B. H., OF BERLIN, GERMANY, A CORPORA-
TION OF GERMANY.

HIGH-SPEED REVOLVING FIELD-MAGNET.

1,376,729.

Specification of Letters Patent.

Patented May 3, 1921.

Application filed September 30, 1915. Serial No. 53,343.

To all whom it may concern:

Be it known that I, REINHOLD RÜDENBERG, a German citizen, and resident of Charlottenburg, near Berlin, Germany, have 5 invented certain new and useful Improvements in High-Speed Revolving Field-Magnets, of which the following is a specification.

With turbo-alternators with rotating field-magnets the maximum output has heretofore been limited by the mechanical strains appearing in the materials, and it seemed impossible to further increase the output of a given type of such turbo-alternators by increasing their velocity.

The present invention relates to a construction, which will allow of increasing the circumferential velocity beyond the heretofore customary limit of about 100 meters 20 per second.

With the object of allowing of increasing the velocity of high-speed armatures, it has been proposed to reduce the masses by substituting for the copper conductors such 25 made of aluminum. This has been done with armatures having an annular winding.

However, the construction of these armatures cannot be applied to field-magnets, because the mechanical strains which are obtained with armature constructions, remain, 30 in consequence of the more favorable conditions with armatures, far below the limit which is reached, in the known designs, with field-magnets.

According to the present invention it is 35 possible to further increase the output of any of the above referred to turbo-alternator types, if the selection of the materials employed in the construction of its field-magnets is made from different points of view 40 than were hitherto customary, and, in particular, formed the basis for the above-mentioned armature designs. In designing such machines the choice of the conductor material was the first step, and this conductor material was so chosen, that it showed a 45 minimum loss. The mechanical strain exerted by the weight of the winding on the machine, then, determined the maximum 50 speed admissible, and therewith also the maximum output of the respective type.

Thus, the two factors, specific resistance and density, were taken separately into consideration. If, however, these two items are jointly considered, essentially more favorable results may be obtained without the losses being increased, as will be apparent 55 from the following.

At the high velocities in question with field-magnets, constructions, such as have 60 been hitherto employed in armatures, are not applicable. Therefore only such constructions will come into consideration for the present invention, in which the centrifugal force acting on the conductor, is received, not by the latter, but by special holding 65 devices.

In the accompanying drawing a field-magnet of this kind is exemplified in diagram.

Figure 1 is a longitudinal section, through such a field-magnet.

Fig. 2 is a cross-section on the line A—B in Fig. 1.

The field-magnet is composed of an iron 75 body 1, provided with journals 2. The middle raised part of said iron body 1 is provided with longitudinal grooves 3, in which the winding of conductor material 6 is placed. At their upper edges, in the circumference of the iron body 1, these grooves are undercut, and closed by means of dovetail keys 4, which are driven into the said undercuttings. These keys serve to hold the winding in the grooves, and prevent its being dashed out therefrom under action of the centrifugal force, when the field-magnet 80 revolves at its high speed.

For further securing and holding the end windings 6 caps 5 are fitted by suitable 90 means over the preferably tapered ends of the iron body 1 and the end windings thereon.

For further securing the conductor winding bandages of a suitable material may be 95 wrapped around the field-magnet and the aforementioned keys.

If, now, with such construction, we compare two exciter coils of different materials indicated in the following by the indices 1 100 and 2, respectively, which are so dimensioned that, at the same excitation, they will show

the same loss in energy, this loss may be expressed, for the respective materials, by the following formula:

$$5 \quad (1) \quad v = \frac{J_1^2 L_1 s_1}{q_1} = \frac{J_2^2 L_2 s_2}{q_2}$$

in which v is the loss in energy, J is the current, L is the length of the conductor, q the section of the same, s the specific resistance. As both coils shall produce the same excitation, they must have the same number of ampere turns, and, therefore, for the same current also the same length per turn in order to have identical conditions for comparison in both cases, excepting, of course, the material itself and its section. Therefore, as J_1 is equal to J_2 and L_1 is equal to L_2 , we get the formula

$$20 \quad (2) \quad \frac{s_1}{q_1} = \frac{s_2}{q_2}$$

or

$$25 \quad (3) \quad \frac{q_1}{s_1} = \frac{q_2}{s_2}$$

where q_1 and q_2 are chosen in accordance with the specific resistance of the materials employed.

With equal length per turn the quotient of the weights q_1 and q_2 of the two windings is proportional the products of section and density (c) of said windings; thus

$$30 \quad (4) \quad \frac{q_1}{q_2} = \frac{s_1}{s_2} \cdot \frac{c_1}{c_2}$$

35 By substituting, according to formula (3) the equivalent for $\frac{q_1}{q_2}$ we obtain the formula

$$40 \quad (5) \quad \frac{q_1}{q_2} = \frac{s_1}{s_2} \cdot \frac{c_1}{c_2}$$

If, now, we assume that the values with the index 1 represent the values for copper, we will obtain, for a different material more favorable results than for copper, provided 45 the product of the specific gravity and the specific resistance for this respective material is smaller than the corresponding product of the respective values for copper. Now the density for copper is $= 8.91 \cdot 10^{-3}$ 50 $\text{kg} \cdot \text{cm}^{-3}$, and the specific resistance is $= 1.75 \cdot 10^{-6} \Omega \cdot \text{cm}$. This product is equal to

$1.56 \cdot 10^{-8} \text{ kg. } \Omega \cdot \text{cm}^{-2}$. Therefore the product of specific gravity and specific resistance of a material superior to copper must be less than $1.56 \cdot 10^{-8} \text{ kg. } \Omega \cdot \text{cm}^{-2}$.

55

Materials suitable for the purpose are, above all, aluminum and various alloys of aluminum and copper.

The lower, therefore, at the same loss, the weight thus obtained for the exciter-winding 60 made of the respective material, the higher the velocity and with it the output of the respective type of machine may be raised. A considerable increase is obtained for aluminum, for which the density is $= 2.7 \cdot 10^{-3}$ 65 $\text{kg. } \cdot \text{cm}^{-3}$, the specific resistance $= 2.87 \cdot 10^{-6}$ $\Omega \cdot \text{cm}$, and the product of both $= 0.775 \cdot 10^{-8}$ $\text{kg. } \Omega \cdot \text{cm}^{-2}$, thus only half as great as that for copper.

If, for example, in the field-magnet shown 70 in the drawing, the winding were made of copper, the holding devices (teeth, keys, bandages and caps) would, at the velocity mentioned, not be able to bear the strain irrespective of the dimensions given to the 75 said parts.

This is made possible, however, by the present invention if the conductor material is selected from such points of view as have hereinbefore been discussed and explained.

Having thus described my invention I claim as new and desire to secure by Letters Patent of the United States:—

1. In electrical alternators in combination a field magnet designed to revolve at an extraordinarily high speed, slots in said magnet, conductors placed into said slots, and holding devices for said conductors adapted to take up the entire centrifugal strain exerted upon said conductors while the magnet revolves, the product of density and specific resistance of the conductor material being smaller than that of copper.

2. In electric alternators in combination a field magnet designed to revolve at an extraordinarily high speed, slots in said magnet, aluminum conductors placed into said slots and holding devices for said conductors adapted to take up the entire centrifugal strain exerted upon said conductors while the magnet revolves.

REINHOLD RÜDENBERG.
